ALFONS L. SEIWERTS, OF BARMEN-LANGERFELD, GERMANY, ASSIGNOR TO THE FIRM
A. ROHLEDER, OF BARMEN, GERMANY

VALENCIENNES LACE

Application September 21, 1929, Serial No. 394,262, and in Germany April 12, 1929.

With the development of the single-thread braiding machine it has become possible to manufacture nearly all kinds of braided lace by machinery and, therefore, in an economical way. Nevertheless there remains just one kind of lace which is comparatively expensive even when produced on braiding machines, namely, the so-called Valenciennes lace. This is a lace comprising the finest of threads, the ground work of which consists of rhombic or polygonal meshes and is interwoven with one or more ribbon-like strips in close weave. These strips necessitate many arrests on the braiding machine and since, moreover, they extend over the whole length of the lace, the manufacture of such lace on the braiding machine is extraordinarily tedious and expensive.

20 A further circumstance which influences adversely the sale of this machine braided Valenciennes lace is the fact that, in France especially, an imitation of the Valenciennes lace is manufactured on the net machine; this indeed, is not so elaborate as the machine braided Valenciennes lace but it is correspondingly cheaper and therefore makes great inroads into the sales of the machine-braided Valenciennes lace.

25 Efforts have, therefore, been made for a long time past to produce machine braided Valenciennes lace more economically. In this connection the recent introduction of the high speed small pitch machine resulted in a certain amount of progress but this, in the case of the machine braided Valenciennes lace, was still insufficient to enter into competition with the lace produced on the net machine.

30 It is the object of the present invention to overcome this difficulty and to render the manufacture of Valenciennes lace on the single-thread braiding machine more economical than heretofore. According to the invention this aim is achieved by working the lace with stationary longitudinal threads, (hereinafter termed warp threads) this being done by making the warp threads replace, in the meshed groundwork of the lace, the obliquely disposed bobbin threads of the

partial braids, while in the pattern they are interwoven as stem threads between the bobbin threads which are arranged in a simple plait.

By this special method of working the manufacture of the lace is rendered materially cheaper. This, on the one hand is brought about by working the lace, not with the expensive closely woven patterned strips but solely with a simple braided weave, that is, without arrests, while, on the other hand, even in the reticulated groundwork of the lace it is possible to secure considerable economy both in bobbin threads and in crossings.

The use of warp threads with single thread braiding machines is, indeed, already known for certain special purposes, whether they be used as auxiliary threads in the temporary formation of tubular structures on the mandrel or in edges of the lace. Warp threads have also been used in filet lace but exclusively as stem threads. According to the present invention on the contrary, the warp threads function, as may be required, sometimes as stem threads in the pattern and sometimes after the fashion of obliquely twisted bobbin threads.

In the accompanying drawings several examples of lace textures according to the invention are illustrated. In these drawings:

Fig. 1 shows a Valenciennes lace produced by the process of the invention with a rhombic groundwork and a simple strip of narrow bands as the pattern.

Fig. 2 shows on an enlarged scale the course of the threads in forming the rhombic net of the groundwork.

Fig. 3 shows the course of the threads in forming the pattern strips.

Fig. 4 shows a lace design with rectangular groundwork meshes and two wavy pattern strips crossing each other, decorative designs being arranged between the pattern strips.

Fig. 5 shows the course of the thread in forming polygonal or substantially round groundwork meshes.

Fig. 6 shows the course of the threads in producing the hexagonal meshes of a special type of groundwork.

Fig. 7 shows the course of the threads in forming a decorative groundwork known under the name of Fond-Chant.

Fig. 8 shows the course of the threads in forming the so-called snowflake decorative groundwork.

Fig. 9 shows a lace with a framed pattern.

Fig. 10 shows to a greatly enlarged scale, the course of the threads in the framework of the pattern according to Fig. 9.

Fig. 11 shows the course of the threads in a Fond-Chant with two warp threads for each three braided threads.

In the example of Fig. 1 *a* is the groundwork of the lace formed of rhombic meshes, through which runs a closely braided strip *b* forming the pattern, the course of which is made to match the scallops at the edge of the lace. While, in hand braided Valenciennes lace the individual cords of the rhombic meshes consist each of four braided threads (see Marie Schütte's "Alte Spitzen", pages 68 and 220, published by Richard Carl Schmidt & Co., Berlin, W. 62 1921), these individual cords, according to the present invention, are made up of a warp thread *d* and only two braided threads *c*, *c'* which are twisted around the warp thread and pass therewith along the slanting run of the cord.

At times at the crossing places of two individual cords, for instance, at the point *f*, the braided threads of the two cords are mutually interchanged so that at such a point a true plait is produced. The warp threads, however, take no part in this plaiting but turn off into the opposite slanting run, since they continue on their plates and are here further intertwined by the newly interchanged pair of bobbins. While the braiding threads, therefore, proceed substantially in diagonal direction across almost the whole width of the lace, the warp threads pursue a zig-zag course which, in the direction of the width of the lace, runs to and fro over only one half of the width of a mesh. This peculiar course of the warp threads is obtained in the present case by working them in at only the least possible tension so that they follow the direction of the bobbin threads which from time to time intertwine with them.

As will readily be seen, this method of working and formation of the cords by comparison with the usual structure embodying four thread cords, results in a substantial saving of material and, above all, in crossings and, therefore, a saving of time.

The same applies substantially to the formation of the pattern strip *b* which hitherto has been exclusively worked in the so-called linen weave whereas, according to the invention, as may be seen from Fig. 3 it is now so worked that the warp threads *d* run straight through and are bound in by the correspond-

ing braiding threads *c* in an ordinary plaited weave.

This permits all the braiding threads to run across the whole width of the pattern strip without arrests whereas, in the linen weave strips hitherto employed extraordinarily frequent and prolonged arrests of the bobbins have been necessary.

In order that the ties in the formation of the pattern strip may be more clearly recognized, the course of the threads in Fig. 3 is highly distorted in the longitudinal direction, so that the braided threads appear to lie in a very inclined direction, whereas, in reality they are beaten up in such close sequence at the braiding point by the crown pick that they lie almost at right angles to the direction of length of the lace and close against one another, forming, in conjunction with the warp threads, a closed cover, as can be seen from Fig. 1. In this connection the warp threads running through have an advantageous effect inasmuch as they hold the remaining braiding threads apart, thus causing the strip to appear more regular and broader.

The further example according to Fig. 4 shows that the new lace is adapted to be made not only with a groundwork of rhombic meshes but also with substantially round meshes for instance, with approximately hexagonal meshes in the so-called lace- or net-ground *a'*. The method of working this lace ground with warp threads can be seen from Fig. 5. As appears on comparing this illustration with Fig. 2 the crossings in the two cases are substantially the same. Since, however, in the second example, a somewhat higher tension is selected for the warp threads, the inter-braided threads at the crossings are thereby drawn apart to some extent and, in place of the rhombic form of mesh, an approximately hexagonal or more rounded off form of mesh is obtained. In other words the crossing places are drawn apart somewhat in the transverse direction of the lace and thus a substantially hexagonal form is imparted to the meshes.

To a similar end the interchange of bobbins at the crossing place may, as shown in Fig. 6 be effected several times. In this way the horizontal lines of the meshes appear to be strengthened. There is then obtained the illustrated type of ground which is also frequently employed in Valenciennes lace, and which resembles the ground of Fig. 4 if the sheet of drawings be rotated through 90°.

In the example shown in Fig. 4 two closely braided strips *b*, *b'* are used which are also worked, in the manner shown in Fig. 3, with warp threads but are entwined with one another in wave form. At the same time the parts *g*, *h* of the lace ground enclosed between them are filled up with a so-called

decorative ground. In the example of Fig. 4 there has been chosen for the places *g* a decorative ground resembling the known "Antwerpener Spelgrond" or called also "Point de Paris" (see Schütte, page 219). The places *h* on the contrary, are filled up with the so called "snowflake ground" or "Point de neige" (Schütte page 215—middle). The representations according to Figs. 7 and 8 of the drawings show, by way of example, how even this kind of decorative groundwork can be formed when using warp threads.

The invention is of course, not restricted to the examples hereinbefore specified, on the contrary, there are many other ways of carrying it into practice. In particular the filling-up of the pattern might be done with other kinds of decorative grounds and the patterns might, as in the so-called Brussels lace be enclosed or bordered by fancy threads.

An example of lace framed round in this manner is illustrated in Figs. 9 and 10. In such a lace, however, by reason of the employment of warp threads special difficulties arise at the places where the fancy threads run, for a long stretch, parallel to the longitudinal edges of the lace as, for instance, at the place *k*, since with the continuous twisting of the fancy thread around the warp thread a forcing up of the ties at the braiding point of the machine would no longer be possible. According to the invention these difficulties are overcome by conducting the fancy thread at given intervals to right or left to an adjacent plate, that is, to a switch plate which carries no warp thread. In Fig. 10 the course of the thread or bobbin with this method of crossing is illustrated. Here *p* is the fancy thread used to frame round the design and *m* the warp thread about which the fancy thread has to be twisted over a long stretch. According to the invention, the fancy thread is carried at the points *q*, *q* on to the temporarily adjacent switch plate, without the warp thread, preferably inside the closely braided pattern while, at the same time, the bobbin thread *t* in the pattern is reversed one plate width ahead in order to avoid collision with the bobbin of the fancy thread. Owing to the fineness of the pattern this irregularity can scarcely be seen in the finished lace with the naked eye; on the contrary, the fancy thread or frame border of the pattern appears to run through completely in straight lines. Only by most careful inspection is a small hole in the lace to be observed at the points *r*, *r* and this does not spoil its appearance.

Furthermore, it is not necessary that, as in the example shown, one warp thread be used for every two braiding threads, for in certain instances a greater or less number of

threads might be used throughout or at individual points in the lace, for instance, two warp threads to every three braiding threads. The last-named way of using warp threads affords, *inter alia*, especially advantageous facilities for forming a ground having the appearance of the known Fond-Chant and shown, to an enlarged scale in Fig. 11. Here the two groups of threads running longitudinally, parallel to the edge of the lace are formed of only one braiding thread *s* and one warp thread *m*, while the obliquely running braids are formed as in the foregoing examples, each of two braiding threads *c*, *c'*, and one warp thread *d*.

Finally, the expression Valenciennes lace is to be interpreted not in a narrow but in a broad sense, so as to include thereunder the known variant forms also.

I claim:—

1. Imitation Valenciennes lace produced on a single-thread braiding machine in which the warp threads in the reticulated ground of the lace are intertwined with the bobbin threads to form therewith obliquely extending partial braids, and in which the warp threads in the pattern of the lace are arranged as longitudinally extending stem threads between the bobbin threads which are braided in a simple plait.

2. Lace of the character set forth in claim 1 characterized in having a plurality of intertwined pattern strips and decorative designs arranged in the intervening spaces and in which the warp threads are drawn through such decorative designs.

3. Lace of the character set forth in claim 1 characterized by the feature that the pattern is framed by an ornamental thread which at those points parallel with the edge of the lace is carried without the warp thread into the braided pattern, while the bobbin thread in the pattern is reversed a plate width ahead of the ornamental thread.

In testimony whereof I affix my signature. 110
ALFONS L. SETWERTS.
